United States Patent Office

Des. 214,076
Patented May 6, 1969

214,076

INSULATED CARAFE

Clyde E. Gillespie, 1025 Valley Road,
Charleston, W. Va. 25302

Filed Mar. 28, 1968, Ser. No. 11,164

Term of patent 14 years

Int. Cl. D7—01

U.S. Cl. D44—21

Fig. 1

Fig. 2

Fig. 3

Fig. 5

Fig. 4

FIGURE 1 is a rear elevational view of my insulated carafe, showing my new design;

FIGURE 2 is a side elevational view thereof;

FIGURE 3 is a bottom plan view thereof;

FIGURE 4 is a top plan view thereof; and

FIGURE 5 is a reduced scale perspective view thereof.

I claim:

The ornamental design for an insulated carafe, as shown.
